[57] CLAIM

The ornamental design for a golf putter head, substantially as shown and described.

DESCRIPTION

FIG. 1 is a perspective view of a golf putter embodying

my novel design of a golf putter head with a shaft and grip shown in broken lines for illustrative purposes only;

FIG. 2 is a side view in elevation of the head of the golf putter shown in FIG. 1 further illustrating the putting face thereof;

FIG. 3 is a side view in elevation of the head of the golf putter shown in FIG. 1 further illustrating the side thereof opposite the putting face;

FIG. 4 is an end view in elevation of the putter head shown in FIG. 1 as seen from the toe;

FIG. 5 is an end view in elevation of the putter head shown in FIG. 1 as seen from the heel;

FIG. 6 is a top view of the putter head shown in FIG. 1;

FIG. 7 is a bottom view of the putter head shown in FIG. 1;

FIG. 8 is a transverse cross-sectional view in elevation of the putter head shown in FIG. 1 taken along the line 8—8 of FIG. 2, as seen in the direction of the arrows; and

FIG. 9 is a longitudinal cross-sectional view in elevation of the putter head shown in FIG. 1 taken along the line 9—9 of FIG. 2, as seen in the direction of the arrows.
